UNITED STATES PATENT OFFICE.

VICTOR KRANICH, OF NEW YORK, N. Y., ASSIGNOR TO FRANCIS S. MARDEN, OF NEW YORK, N. Y.

ELECTRIC SWITCH.

1,323,368.

Specification of Letters Patent.

Patented Dec. 2, 1919.

Application filed July 3, 1916, Serial No. 107,271. Renewed April 22, 1919. Serial No. 291,952.

To all whom it may concern:

Be it known that I, VICTOR KRANICH, a citizen of the United States, and a resident of the borough of Manhattan, city, county, 5 and State of New York, have invented certain new and useful Improvements in Electric Switches; and I do hereby declare the following to be a full, clear, and exact description of the invention, such as will enable others skilled in the art to which it 10 pertains to make and use the same.

This invention relates to switches for electric circuits and more particularly to a switch of the type commonly known as a 15 snap-switch.

It is an object of the invention to produce a device of simple construction and reliable operation for causing a quick break of an electric circuit with a minimum amount of 20 arcing at the contact surfaces of the switch.

It is a further object of the invention to produce a switch in which the parts which cause breaking of the circuit shall be adapted to be easily altered to bring fresh portions of their surfaces into contact or in 25 which these parts may be quickly replaced by new ones when they become worn by prolonged operation.

Other objects and advantages of the invention will be apparent from the following description taken in connection with the accompanying drawings, in which—

Figure 1 is a front elevation of the switch showing the face plate and operating but- 30 ton;

Fig. 2 is a rear elevation showing the switch in circuit-closing position;

Fig. 3 is a view similar to Fig. 2 but showing the switch in open circuit position;

Fig. 4 is a view, principally in section, along the line 4—4 of Fig. 2; and

Fig. 5 is a view principally in section along the line 5—5 of Fig. 2.

Referring to the drawings, in which similar reference characters denote similar parts throughout the several views thereof, 10 represents a base of any desired insulating material upon which the parts of the switch are mounted. 11 is a contact strip attached 15 to the base by means of a screw 12 which at its end is provided with a nut 13 to serve as a binding post for connecting a circuit wire to the switch. The other end of strip 11 is attached to the base 10 by a metallic bushing 14 screw-threaded at one end to receive a

nut 15 by which the strip 11 may be securely clamped in place.

Through the bushing extends a shaft 16 which at the upper end is expanded into a plate 17 to which an insulating block 18 is 60 attached by means of screws 19. The operating button 20 may be formed integral with or attached to the block 18 in any convenient manner. Surrounding the block 18 is a face plate 21 which is attached to the base 10 65 by blocks of insulation 22. The face plate is preferably formed of insulating material and has a central depression within which the button 20 is placed, the outer surface of the latter being approximately flush with 70 the top of the face plate. The designations "Off" and "On" may be placed on the surface of the plate to show the position of the removable members of the switch. A recess 23 is cut around the edge of the upper face 75 of the plate so that the latter may be set into a plate forming a part of any electrical apparatus with which it is desired to use the switch. The latter may be retained in place by bolts passing through holes 24 in the face plate.

Surrounding the other end of the shaft 16 and attached thereto by a pin 25 is a sleeve member 26 which serves as a bearing for a movable contact arm 27. This arm is 85 formed with a socket 28 at one end and a latching projection 29 at the other. A short carbon rod 30 may be placed within the socket and retained in any manner. Coiled about the outer end of the shaft 16 is a 90 spring 31 retained in place by a nut 32 and washer 33. One end of this spring is attached to the arm 27 by a pin 34 while the other end thereof is attached to the sleeve member 26 by pin 35 extending beyond the 95 contact arm 27.

A binding post 40 forming the other terminal of the switch is mounted on the base 10. To 40 is attached a spring finger 41 having a main contact 42 shaped to fit 100 against the outer surface of the socket 28 when the switch is in circuit closing position. Another spring finger 43 is attached to 40. This latter finger has a socket 44 adapted to receive a short carbon rod 45 105 the outer end of which comes in contact with the outer end of carbon 30 when the switch is in circuit closing position, these parts thus constituting auxiliary contacts.

The means for retaining the arm 27 in 110

2

circuit-closing position until such time as it should be released consists of a latching device comprising a detent arm 50 pivoted to a post 51 which may be attached to the base 5. 10 by a nut 52, there being a head 53 on the end of the post. A spring 54 is coiled about the end of the post and retained in place by a nut 55. One end of the spring is attached to the nut 52 by being inserted 10 in a hole therein as at 56 while the other end of the spring is brought around the side of 50 as at 57. The action of the spring is to hold the detent 50 under the projection 29 of the movable contact arm to retain the latter in circuit-closing position. A tripping arm 58 extends from the side of 50 into the path of the pin 35.

Assuming the parts of the switch are as shown in the circuit closing position of Fig. 2 and it is desired to open the switch the operation will be as follows: The button 20 is rotated to the "Off" position. This causes the shaft 16 and the sleeve member 26 attached thereto to rotate in a direction to bring pin 35 against the end of the tripping arm 58. At the same time the spring 31 is put under tension because its other end is attached to arm 27 which is held by detent 50. When pin 35 reaches 58 further motion will release the detent and the spring will then cause the arm 27 to rotate rapidly. The circuit will be first broken between the main contacts 28 and 42, while the carbons 30 and 45 will remain momentarily in engagement. It will be noted that the contact face of 45 is set so that it is not perpendicular to a line passing through the axis of the movable contact arm. It follows from this arrangement that as contact 30 moves over contact 45 the preceding portion of the face of the former contact will gradually recede from the face of the latter leaving only the following portion of the face of the former in contact until that 45 portion finally passes off of 45. Thus the arcing which occurs at the break of the circuit will take place at or near the edges of the carbon contacts and by slightly altering their positions in the sockets from time 50 to time their period of use can be considerably lengthened. Whenever it is necessary to replace them it can be done quickly by merely removing the old ones and inserting new ones in the sockets.

55. To close the circuit the button 20 is turned to the "On" position. This will rotate the shaft 16 and also the arm 27 because the pin 35 engages the edge of the latter. Contact will first be made between the preceding 60 edge of carbon contact 30 and the face of carbon contact 45 after which the two contacts will reach the position shown in Fig. 2, at which time the latch projection 28 will ride over the detent 50 and be retained in place until a subsequent release. At the

same time contact finger 42 will come firmly in contact with the outer surface of socket 28, over which it has a sliding or wiping movement due to the resiliency of spring finger 41.

70 Various modifications or changes in the details of the construction of my invention may be made without departing from the principle thereof.

I claim:

1. An electric switch, comprising, in combination, a base, a shaft rotatably mounted on the base, a main contact rotatably mounted on said shaft, an auxiliary contact associated with said main contact, a main contact device adapted to engage said main contact, an auxiliary contact device adapted to engage said auxiliary contact, means for retaining said main and auxiliary contacts in engagement with their corresponding contact devices, means operable by said shaft for releasing said retaining means and means for causing separation of said main contact and contact device and subsequent separation of said auxiliary contact and contact device.

75 2. An electric switch, comprising, in combination, a base, a shaft rotatably mounted on said base, an arm rotatably mounted on said shaft, a main contact upon said arm, an auxiliary contact upon said arm, a main contact device adapted to engage said main contact, an auxiliary contact device adapted to engage said auxiliary contact, means for retaining said main and auxiliary contacts in engagement with their corresponding contact devices, means operable by said shaft for releasing said retaining means and means for causing separation of said main contact and contact device and subsequent separation of said auxiliary contact and contact device.

90 3. An electric switch, comprising, in combination, a base, a shaft mounted on said base, an arm rotatably mounted on said shaft, means connecting said shaft and said arm, a main contact upon said arm, an auxiliary contact upon said arm, a main contact device adapted to engage said main contact, an auxiliary contact device adapted to engage said auxiliary contact, means for retaining said main and auxiliary contacts in engagement with their corresponding contact devices, means operable by said shaft for increasing the effect of said connecting 110 means and for thereafter releasing said retaining means to cause separation of said main contact and contact device and subsequent separation of said auxiliary contact and contact device.

95 4. An electric switch comprising, in combination, a base, a shaft mounted on said base, an arm rotatably mounted on said shaft, means connecting said shaft and said arm, a main contact upon said arm, a re-

movable auxiliary contact associated with said main contact, a main contact device adapted to engage said main contact, an auxiliary contact device having a removable contact adapted to engage said auxiliary contact, means for retaining said main and auxiliary contacts in engagement with their corresponding contact devices, means operable by said shaft for putting said connecting means under tension and for thereafter releasing said retaining means to cause separation of said main contact and contact device and subsequent separation of said auxiliary contact and contact device.

5. An electric switch comprising, in combination, a base, a shaft mounted in said base, means for rotating said shaft, an arm rotatably mounted on said shaft, a spring connecting said shaft and said arm, a main contact on said arm, an auxiliary contact of carbon or the like associated with said main contact, a main contact spring adapted to engage said main contact, an auxiliary contact spring having a removable contact of carbon or the like adapted to engage said auxiliary contact, a detent for retaining said main and auxiliary contacts in engagement with their corresponding contact springs, a pin associated with the shaft for retaining one end of said connecting spring and adapted when said shaft is rotated to

10
15
20
25
30

cause a tension in said connecting spring and to thereafter release said detent to cause separation first of said main contact and contact spring and thereafter of said auxiliary contact and contact spring. 35

6. An electric switch comprising, in combination, a base, a shaft mounted in said base, means for rotating said shaft, an arm mounted on said shaft, said arm being formed with a socket at one end, means connecting said shaft and said arm, a spring finger adapted to engage the outer surface of the socket, an auxiliary contact inserted in said socket, an auxiliary spring finger having a socket at one end, a contact member inserted in said socket and adapted to engage said auxiliary contact, the engaging surfaces of said contacts being so related to each other that contact is first made between the edge of the contact located in the socket on the arm and the central portion of the face of the other contact, means for retaining the spring finger and socket and said auxiliary contacts in engagement, and means operable by said shaft for releasing said retaining means to cause said spring finger and socket to first break contact and thereafter said auxiliary contacts to break circuit. 40 45 50 55

In testimony whereof I affix my signature. **60**

VICTOR KRANICH.
